[57] ABSTRACT

In a multicolor offset printing machine, apparatus for circumferentially adjusting the form or perfecting cylinder for register printing, there is provided two pairs of intermeshing gears. The first pair includes two helical gears coaxially arranged and axially shiftable relative to each other. One of these first gears carries a third gear engaging a pinion whose supporting rod is secured to the perfecting cylinder. The second pair of gears is jointly mounted to be rotatable about an axially shiftable axle which when so shifted causes the gears of the first pair to be angularly offset with respect to each other. This causes simultaneous displacement between the third gear means and the pinion which causes the perfecting cylinder to be correspondingly offset. The supporting rod of the pinion is also provided with means permitting it to be angularly adjusted thereby causing axial offset of the gears and consequent adjustment of the form cylinder with respect thereto.

APPARATUS FOR THE ADJUSTMENT OF A FORM CYLINDER

BACKGROUND OF THE INVENTION

The present invention relates to apparatus for the circumferential adjustment of the form or perfecting cylinder for register printing particularly on multicolor offset printing machines.

In multicolor offset printing machines it is necessary to provide for the continuous and accurate adjustment of the perfecting cylinder with the printing cylinder so that quality register printing can be obtained. It is necessary that this adjustment be carried out when the printing machine is in operation so that precise and accurate registration of the color can be obtained. It is also necessary to provide for such adjustment when the machine is stopped so that the machine may be as accurately set as possible prior to the institution of any printing.

One of the known devices for the circumferential adjustment of the perfecting cylinder for register printing includes the use of a pair of gear wheels, one of which being a helical gear which is rotatably mounted on the side wall of the printing machine. The other gear of the pair of gear wheels is a spur gear which is coaxially attached to the perfecting cylinder. Engaging with the helical and spur gears is a pair of fixedly connected pinions which are mounted on a shiftable countershaft. The end of the countershaft is provided with a thread. A corresponding nut formed by a body which is affixed to the side wall of the printing machine engages the threaded portion. The countershaft has the function of a screw which is either directly or by means of an additional transmission linkage connected with a control knob. A disadvantage of the above device is that a spur gear connected to the perfecting cylinder must engage with the helical gear in order to obtain the circumferential adjustment of the perfecting cylinder. The spur gear results in the production of excessive vibration and noise which have a substantially negative effect upon proper register printing and to the perfecting of the coloration of the printing surfaces.

Another known device has a control mechanism arranged in the hollow shaft of the perfecting cylinder. The disadvantage of this type of arrangement lies in the fact that the shaft of the perfecting cylinder must be hollow and consequently is considerably weaker and less rigid than a solid cylinder shaft and consequently the cylinder shaft tends to bend and become deformed thus disturbing proper registration.

It is an object of the present invention to provide an arrangement for the adjustment of the perfecting cylinder which overcomes the disadvantages and defects of the prior known devices.

It is a further object of the present invention to provide apparatus for the circumferential adjustment of the perfecting cylinder either when the machine is stopped or during the continuous operation of the press and while printing is being effected.

It is a further object of the present invention to provide apparatus for the adjustment of the perfecting cylinder which is simple in construction yet which eliminates vibration and excessive noise and which maintains perfect registration once so adjusted during the continuous printing operation.

The above objects, other objects and numerous advantages will be apparent from the following disclosure of the present invention.

SUMMARY OF THE INVENTION

In accordance with the present invention a multicolor offset printing machine having a printing cylinder and a perfecting cylinder is provided with apparatus for circumferentially adjusting the form cylinder for register printing. The apparatus comprises a supporting shaft extending axially from one end of the form cylinder and about which a first gear means comprising an annular helical main gear and an annular helical driven gear are arranged. The main helical gear has a hub rotatable about the supporting shaft while the helical drive gear is coaxially arranged and rotatable with respect to the main gear. Second gear means is provided adjacent to the first gear means and is adapted to mesh with and coact respectively with the main and the drive gears. The second gear means is rotatably mounted about an axially movable axle so that the second gear means itself is reciprocally translatable with respect to the helical main and drive gears. A third gear means is secured to the hub of the main gear adjacent the end of the perfecting cylinder. A pinion engages the third gear means and is fixedly mounted on a rod extending into and secured within the perfecting cylinder. The helical drive gear is adapted to be driven during the operation of the printing machine to effect conjoint rotation of the perfecting cylinder with it and consequently the rotation of the perfecting cylinder. The axial shifting of the axle on which the second gear means is rotatably mounted causes a relative angular displacement of the helical main gear with respect to the helical drive gear, consequently causing the third gear means to angularly displace the pinion and simultaneously to angularly displace the perfecting cylinder relative to the helical main gear and thus relative to the printing cylinder. Preferably the axially movable axle holding the second set of gears is manually operable. Thus the invention provides the advantage of enabling the manual adjustment of the perfecting cylinder with respect to the printing cylinder in a quick and easy manner during the continued operation of the printing machine. When the machine is stopped, a rough adjustment may be carried out by angularly adjusting the pinion to move the helical gear means, in a reverse manner, so as to enable the relative adjustment between it and the perfecting cylinder to be effected. Thereafter a more accurate registration of the perfecting cylinder may be achieved when the machine is put back into printing action. As a result it is not necessary to stop the machine for each minor adjustment of the perfecting cylinder.

Preferably, the helical main gear and the helical drive gear each have teeth inclined in an opposite direction to that of the other. As a result the axial movement of the second gear system which intermeshes with the helical main and drive gears effects an angular offset which is significantly larger than would be otherwise expected, consequently permitting a more accurate adjustment to be made.

Preferably, the third gear means comprises a gear wheel secured to the helical main gear and a gear collar adjustably mounted on the gear wheel so as itself to be angularly offset with respect to it. Adjustment of this pair of gears enables the intermeshing with the pinion to be made with a great deal of perfection eliminating

backlash vibration and noise between them. Still further in accordance with the present invention the supporting rod holding the pinion is retained in a holder mounted within the perfecting cylinder. The holder is provided with means by which the angular disposition of the rod may be adjustably fixed and with means for securing the rod in fixed position once this adjustment is made. In this manner the rough adjustment mentioned earlier can be easily made by merely rotating the pinion support rod.

From the foregoing it will be seen that the present invention provides a considerable saving in make ready time necessary for arranging the printing machine with the proper circumferential adjustment of the perfecting cylinder. Quicker and easier manipulation is obtained and a more accurate register printing is effected.

Full details of the present invention are given in the following description of its preferred form and is shown in the accompanying drawings.

BRIEF DESCRIPTION OF THE DRAWINGS

In the drawings:

FIG. 1 is a front view of one of the latter ends of a form cylinder showing in partial section the apparatus of the present invention arranged therewith,

FIG. 2 is a sectional view taken along line 2—2 of FIG. 3 showing in partial end view a portion of the device of the present invention,

FIG. 3 is an enlarged sectional view of the apparatus as viewed in the direction of line 3—3 of FIG. 2,

FIG. 4 is an enlarged plan view, partially in section, showing a portion of the perfecting cylinder and its adjusting pinion,

FIG. 5 is a partial sectional view taken along line 5—5 of FIG. 4,

FIG. 6 is a partial sectional plane taken along line 6—6 of FIG. 4, and

FIG. 7 is a continuation of the partial section of FIG. 1 showing the mounting of the axially movable adjusting shaft of the laterally opposite end of the machine frame, shown in FIG. 1.

DESCRIPTION OF THE PRESENT INVENTION

As seen in FIG. 1 only a portion of one of the lateral ends of a conventional multicolor offset press is shown. A form cylinder 4 is provided with a supporting shaft 3 extending outwardly along its central axis and journaled for sliding rotation within a cylindrical hub 38. The hub 38 is provided with a main gear, generally depicted by the numeral 1, formed by integrally casting or machining between the ends of the hub 38 a radially extending disc 38a. The peripherally outer end of the disc 38a is stepped to provide an outer shoulder 38b and an inner shoulder 38c of lesser diameter. The peripheral surface of the outer shoulder 38b is provided with a helical tooth gear configuration. Mounted so as to be slidably rotatable about the inner shoulder 38c is an annular drive gear 2 having an outer peripheral surface also provided with a helical tooth gear configuration, the direction of pitch or incline of which is opposite to that of the helix of the main gear 1.

The disc 38a is situated to provide a small inner hub portion 38d on which is mounted a spur type gear wheel 14. The gear wheel 14 is provided with an elongated base, forming a cylindrical shoulder 14a on which a collar gear 15 also of the spur type is rotatably mounted. The gear wheel 14 and the collar 15 are se-

cured, as seen in FIG. 2 to the helical main gear 1 by a plurality of bolts 16 which have their ends threaded in bores formed in the disc 38a. Each of the bolts passes through an arcuate (circular segment) slot 29 formed in the collar gear 15 which thus allows the collar gear 15 to be rotatably adjusted with respect to the gear 14.

The collar gear 15 is, in addition to the arcuate slots 29, provided with a plurality of circular-segmented or arcuate grooves 30 formed on its inner face adjacent to the gear wheel 14. A similarly arcuate groove 39 is formed on the facing surface of the gear wheel 14 so as to form with the grooves 30 an arcuate box. A compression spring 17 is retained in the boxes formed by the grooves 30 and 39, one half of the spring 17 lying in the groove 30 while the other half lying in the groove 39. The spring 17 thus resiliently biases the gear wheel 14 and the gear collar 15 to one of their extreme angular relative positions against which bias they may be subsequently adjusted by setting of the bolts 16. The head of the bolts 16 (FIG. 2) overlaps the edges of the slot 29 so that when the bolts are tightened, the gear wheel 14 and collar 15 are secured in relatively fixed positions by being compressed against each other. The range of rotary adjustment or turning of the collar gear 15 relative to the gear wheel 14, and thus relative to the helical main gear 1 is defined and limited by the extent of the slot 29.

The spur type gear wheel 14 and the gear collar 15 engage with a single actuating pinion 18 fixed at the end of a rotatable shaft 19 mounted within a holder 21 (FIG. 3). The holder 21 is fixed within the perfecting cylinder by being mounted on the end face or side part of the perfecting cylinder 4 by at least a one bolt 24. The holder 21 is split along a planar slot 42 extending from one end to the other through the cylindrical bore adapted to receive the shaft 19. The rotatable shaft 19 is provided with a threaded circular rack or screw gear 20 with which a rotatable pinion 22, also journaled in the holder 21, meshes (FIG. 6). The pinion 22 has a bolt head so that it may be easily manipulated with a suitable tool. Rotation of the pinion 22 results in rotation of the rod 19 on which the actuating pinion 18 is mounted. The rotatable rod 19 is axially retained in the holder 21 by a securing screw 25 whose end is received in an annular slot 43 formed in the surface of the rod 19. Thus during rotation of the rod 19 the rod may be prevented from axially being removed from the holder 21. The rotatable rod 19 is clamped in fixed rotative position after adjustment by a locking screw 23 which extends transversely through the planar slot 42. The locking screw 23 may be loosened and tightened as desired to clamp or free for rotatable rod and thus permit adjustment of the actuating pinion 18 into selected position.

Returning to FIG. 1, the outer end of the hub 38, which is longer than its inner end is surrounded by a pair of spaced radial ball bearing structures, generally defined by the numeral 6. The outer races of the bearing structures 6 are mounted in a cylindrical body or sleeve 5 having a radially extending flange 5a which is securely fixed in the adjacent side wall 27 of the frame of the printing machine. In this manner the perfecting cylinder 4 is supported at this end by the machine frame. The opposite end of the perfecting cylinder is supported in a spaced parallel side wall 40 seen in FIG. 7, in conventional manner. The end of the shaft 3 is furthermore abutted by a ball type axial bearing held by

suitable retaining means fastened or keyed in the usual manner to the hub 38 and is axially retained by a nut abutting against the wall 27.

Arranged above the helical main gear and the helical drive gear forming a first pair of gear means is an intermeshing and coaxing pair of pinion gears 7 and 8 forming a second pair of gear means. The pinion gear 7 meshes with the helical drive gear 2 and is provided with an axially extending shoulder on which the second pinion gear 8 is securely fixed so as to mesh with the helical main gear 1. This arrangement of two pinion gears 7 and 8 is advantageous in that the gears may be more easily made and more easily arranged so that they mesh perfectly with the respective helical drive gear 2 and main gear 1. The pinion gears 7 and 8 are rotatably journaled about an elongated axle 9 seen in FIG. 1 and in extension in FIG. 7. The shaft 9 is provided with a necked-down end portion about which a pair of radial ball bearings are arranged. The pinion 7 is fixed to the outer race of the radial ball bearings so as to be incapable of axial movement. The axial position of the pinion 7 is further secured by a spacer member 36 which fits over the outer end of the necked-down portion of the axle 9 and abutting the inner race of the outer ball bearing. This displaces the inner ball bearing against the shoulder forming the necked-down portion of the shaft 9. The spacer 36 is secured to the end of the shaft 9 by a screw 36a thus firmly holding the pinion 7, and the pinion 8 mounted about it, against axial displacement in either direction.

The shaft 9 is, however, axially displaceable by slidably mounting the spacer 36 in a cylindrical bushing 10 which is fixed to the side wall 7 of the printing machine as seen in FIG. 1, and by mounting the central portion of the shaft 9 in a tubular sleeve 35 which has an arcuately enlarged outer cup-like portion 35a fixed at its edges to the wall 27 by screws 35b. As seen in FIG. 7 the tubular spacer 35 extends transversely across the printing machine, about the shaft 9 terminating in a radial flange 35c secured by bolts 35d to the opposite wall 40 of the printing machine. The shaft 9 extends through a hole in the wall 40 and has a sleeve 11 surrounding it. The sleeve 11 is fixed against axial and rotational movement to the wall 40 and is provided with an internal screw thread 11a. The shaft 9 is provided with a conforming thread 9a. The shaft 9 extends further outwardly beyond the wall 40 and has a knurled knob 12 secured to it by a set screw 37. An enlarged covering member 13 is secured by a second set screw 37a to the fixed sleeve 11. The cover member 13 has an enlarged cup which surrounds the inner end of the knob 12. The peripheral wall of the cover 13 is provided with a hole in which a ball 28 is resiliently retained in conventional manner, to press against the surface of the knob 12. The knob 12 at this end is provided with an annular groove, or if desired a plurality of discreet grooves having a defined axial extent, uniformly spaced about the circumference of the knob, as indicated by the numeral 41. Thus, manipulation of the knob 12 will rotate the shaft 9, causing the shaft 9 to be axially displaced by the reaction of its thread 9a with the threads 11a. The axial displacement causes the shaft 9 to reciprocate axially with respect to the spaced walls 40 and 27 and thus with respect to the helical main drive gears shown in FIG. 1. The angular position and axial extent of the displacement of the shaft 9 is limited and defined by the position of the ball 28 in the annular groove or in a par-

ticular one of the discreet grooves all generally depicted by the numeral 41.

Returning again to FIG. 1, the main gear 1 is provided with an annular disc 31 having a right angle cross section; the vertical leg of which is fixed to the disc portion 38a while the horizontal leg portion extends toward a slidable ring 33 mounted about the end of the perfecting cylinder 4 and in which an axial slot 34 extends annularly about its central axis. The horizontal leg of the disc 31 is provided with a suitable scale, having indicia of angular displacement, while the slidable ring 33 is provided with an indicating arrow 32 pointing to the scale 26.

Suitable gear means (not illustrated) is provided for engagement with the drive gear 2 whereby the device as a whole may be driven. The helical drive gear 2 engages with the pinion 7 which rotates together with its fixedly connected pinion 8 on the axially displaceable shaft 9. Thus conjoint rotation is obtained via the pinion 8 on the helical main gear 1. Under normal operating conditions the pinion 18 is in clamped and fixedly locked position as is the third gear means comprising the spur gear 14 and the collar 15 thus rotation of the helical main gear 1 will carry with it the perfecting cylinder 4, the shaft 3 rotating with the hub 38.

The circumferential adjustment of the perfecting cylinder 4 for effective register printing, is carried out during the printing operation by turning the knob 12, seen in FIG. 7. As a result of the rotation of the knob 12 the shaft 9 is axially displaced by being screwed into or out of the thread of the sleeve 11. The axial displacement of the shaft 9 carries with it the pinion 7 and the pinion 8 as will be obvious from FIG. 1. Since the pinions 7 and 8 both have teeth which mesh and coat with those of the helical drive gear 2 and the main gear 1, they too are provided with teeth which are inclined in a direction opposite to the other. Thus, by the axial movement of the pinion 7 and the pinion 8, the main helical gear is angularly offset and turned relative to the drive gear 2, the drive gear 2 being slidably mounted on the disc 38a. The angular offset of the helical main gear 1 carries with it the gear wheel 14 and the collar gear 15 which is firmly fixed with the helical main gear 1 by the bolts 16. Since the gear wheel 14 and the collar gear 15 engage the pinion 18 which is secured at the end of the rod 19, which in this case still remains firmly clamped to the holder 21, the perfecting cylinder 4 is also angularly offset and thus also circumferentially adjusted for register printing, with respect to the printing cylinder. The helical drive gear 2, due to the fact that its teeth are inclined in an opposite direction to the teeth of the helical main gear 1, is turned in an opposite direction from that of the helical main gear 1. By thus turning the helical gears in opposite directions, a larger range of circumferential adjustment of the perfecting cylinder is made possible by very small axial displacements of the shaft 9.

The circumferential adjustment of the perfecting cylinder with respect to the printing cylinder, for register printing, while the printing machine is stopped is carried out in the following manner: The locking screw 23 (FIG. 5) by which the rotatable rod 19 is clamped in fixed position is loosened, thus permitting the screw pinion 22 to be rotated. On rotation of the screw pinion 22 the screw gear 20 formed on the rod 19 allows the rod 19 to be pivoted about its central axis. In this manner the actuating pinion 18 is itself turned and since it

engages with the pair of gears formed by the wheel gear 14 and the collar gear 15, which gears are in fixed position due to the fact that they are securely fixed to the helical main gear 1 which because the machine is in stopped condition, remains fixed. Thus the rotation of the pinion 18 has a reverse action causing angular offset of the perfecting cylinder 4 in a direction opposite to the direction of the turning of the main helical gear 1 and in a direction opposite to the turning of the helical drive gear 2, since both remain fixed. Once this angular adjustment is made the rod 19 can again be clamped into its fixed position by manipulation of the bolt 23.

The extent and value of the angular offset of the perfecting cylinder can be registered and controlled on the scale 26.

From the foregoing, it will be seen that the adjustment of the perfecting cylinder is obtained by the employment of a first pair of coaxially and relatively rotatable gears (1 and 2) which are angularly offset and movable by a second pair of gears (7 and 8). One of the angularly adjustable gears is provided with a third gear means which engages a pinion normally fixed in the perfecting cylinder so that upon its axial offset the third gear will cause corresponding angular adjustment of the perfecting cylinder. The apparatus is relatively simple to coaxially and relatively angularly adjustable gears are capable of a wide range of adjustment and preferably have helical gear faces extending in opposite directions with respect to each other so that this wide range of adjustments can be obtained. The second set of gears meshing with the angularly adjustable gears are preferably angularly offset which translated to the helical gear structure permits an angular adjustment. The third gear means is comprised of a pair of gears which themselves are angularly adjustable with respect to each other and provided with resilient biasing means in which manner vibration and backlash characteristics can be easily avoided.

Various modifications and changes have been suggested in the disclosure, others will be apparent to those skilled in the art. It is therefore intended that the present disclosure be taken as illustrative only of the present invention and not limiting of its scope in any manner.

What is claimed is:

1. In a multicolor offset printing machine having a printing cylinder and a perfecting cylinder, apparatus for circumferentially adjusting the perfecting cylinder for register printing comprising a supporting shaft extending axially from one end of the perfecting cylinder, first gear means comprising an annular helical main gear having a hub rotatably arranged about said supporting shaft and an annular helical drive gear coaxially mounted on a first shoulder of said hub and rotatable with respect to said main gear, second gear means adapted to mesh with and coact respectively with said main and drive gears, said second gear means being rotatably mounted about an axially movable axle, third gear means secured to said main gear on a second shoulder thereof adjacent the end of the perfecting cyl-

inder, a pinion engaging said third gear means and fixedly mounted on a rod extending into the end of said perfecting cylinder and secured thereto, said helical drive gear being adapted to be driven during operation of said printing machine to effect conjoint rotation of said helical main gear and said perfecting cylinder, whereby axial shifting of said axle would cause relative angular displacement of said helical main gear and said helical drive gear consequently causing said third gear means to angularly displace said pinion causing said rod to angularly displace said perfecting cylinder relative to the helical main gear.

2. The apparatus according to claim 1 wherein the helical main gear has teeth inclined in an opposite direction to the teeth of the helical drive gear.

3. The apparatus according to claim 2 wherein said second gear means comprise a pair of gears each having helical teeth conforming to said main gear and drive gears respectively.

4. The apparatus according to claim 1 wherein said pinion rod is retained in a holder mounted within said cylinder, said holder being provided with means for adjustably fixing the angular position of said pinion rod about its longitudinal axis, wherein the relative position of the perfecting cylinder and the main gear are angularly adjustable.

5. The apparatus according to claim 1 wherein the third gear means comprises a spur gear secured to said helical main gear and a gear collar adjustably mounted on a shoulder of said gear wheel to be angularly adjustable with respect thereto.

6. The apparatus according to claim 5 wherein the gear collar is provided with a plurality of arcuate slots, screw means extending through said arcuate slots and through said spur gear to be threadedly retained in said helical main gear.

7. The apparatus according to claim 6 in which the facing surfaces of said spur gear wheel and said spur gear collar is provided with a plurality of paired arcuate grooves, a spring located in each pair of grooves resiliently biasing said gear collar and spur gear wheel against angular relative rotation.

8. The apparatus according to claim 4 including means for clamping said pinion rod in said holder in fixed adjusted position.

9. The apparatus according to claim 1 including a disc fixed on the helical main gear, said disc being provided with an axial leg extending into a circular slot formed in a slide ring mounted over the end of said perfecting cylinder, said disc being provided with a scale and said ring being provided with an indicator marking located opposite to said scale.

10. The apparatus according to claim 1 wherein the means for axially moving said axle comprising a sleeve having an internal threaded bore surrounding said axle, said axle being formed with a conforming threaded surface, and means for rotating said axle whereby the interaction of said threaded surfaces causes axial displacement of said axle.
